UNITED STATES PATENT OFFICE.

SAMUEL E. SHAFFER, OF ELKHART COUNTY, INDIANA.

MOLD.

1,080,850.

Specification of Letters Patent.

Patented Dec. 9, 1913.

Application filed August 20, 1912. Serial No. 716,063.

To all whom it may concern:

Be it known that I, SAMUEL E. SHAFFER, a citizen of the United States, residing in the county of Elkhart and State of Indiana, have invented certain new and useful Improvements in Molds, of which the following is a specification.

My invention relates to cement molds and has particular reference to a cement post mold.

An object of the invention is to provide a mold adapted to form cylindrical or tapered posts having extensions thereon adapted to serve as braces.

A further object of the invention is to provide a post having these extensions so disposed as to be adapted for use in either corners or straight line fences.

An important object is to provide means whereby the number of braces may be varied without altering the construction of the main portion of the device.

Another object is to provide a device of this character which is inexpensive in its manufacture, simple and efficient in operation, and durable in service.

Other objects will be made apparent during the course of the following specification.

Referring to the drawings wherein is illustrated a preferred embodiment of my invention: Figure 1 is a side elevation of the mold set up for use, Fig. 2 is a cross-sectional view thereof on the line 2-2 of Fig. 1, Fig. 3 is a cross-sectional view showing the mold provided with only one brace mold, Fig. 4 is a perspective view of the detachable plate used for closing one of the openings in the mold, Fig. 5 is a cross-sectional view through one of the brace molds, Fig. 6 is a perspective view of a closure plate for the same, Fig. 7 is a detail sectional view showing the connection between the upper and lower halves of the mold, Fig. 8 is a detail sectional view showing guides and fastening means, Fig. 9 is a detail sectional view showing another of the guides, Fig. 10 is a fragmentary plan view of one of the locking tubes, Fig. 11 is a similar view of one of the sliding locks adapted to coöperate therewith, Fig. 12 is a cross-sectional view through the locking tube with the sliding lock in place, and, Fig. 13 is an elevation of the finished post.

Referring more particularly to the drawings, the numerals 1 and 2 designate upper and lower mold sections which are prefer-

ably formed tapered. These upper and lower sections fit together and are prevented from displacement by means of a band 3, which is secured to the upper section 1 and overlaps the lower section 2, as shown at 4. The sections 1 and 2 are composed of semi-cylindrical plates, 5 and 6, and 7 and 8, respectively. In order to secure the semi-cylindrical plates together upon the inner face of the plates 6 and 8 I provide longitudinal strips 9 secured as by rivets adjacent their rear edges upon said plates 6 and 8. The plates 6 and 8 have their edges spaced slightly away from said plates. This construction provides pockets 10 for the reception of the edges of the plates 5 and 7. In order to prevent accidental displacement of the two semi-cylindrical portions, I provide a plurality of staples 11 adjacent the edges of the plates 5 and 7 adapted to be engaged by a corresponding number of eyes 12 secured upon the adjacent edges of the plates 6 and 8. After the eyes 12 have been placed over the staples 11 locking pins 13 are inserted to prevent the displacement of the eyes. It will be noted that the band 3 is formed in two parts having their edges in alinement with the edges of the two main semi-cylindrical plates. By this construction it will be seen that after the two lower semi-cylindrical plates 7 and 8 are placed together and locked by means of the staples, eyes and pins 11, 12 and 13, and the upper plates 5 and 6 are assembled in the same manner and locked over the lower section 2 by means of the band 3, a rigid frusto-conical shell is provided.

In order to form wings or extensions to serve as braces for the post, I provide brace molds indicated as a whole by the numeral 14. These brace molds comprise triangular plates 15 having their lower edges 16 rolled. The rear edges of the plates 15 are bent as shown at 17, and are adapted for slidably engagement with similarly bent strips or guides 18 secured upon the plate 8. The plates 15 are arranged in pairs and are spaced apart and are in alinement with openings 19 formed in the plate 8. It will thus be seen that the space between the plates 15 is in effect a continuation of the space within the frusto-conical mold. In order to hold the plates 15 in their spaced relation I provide locking tubes 20 adapted to fit within openings 21 in the plates. These locking tubes are tapered and are substantially cir-

cular in cross-section. The tubes 20 are split and one edge is bent inwardly upon the tube as shown at 22 and then bent again as shown at 23 to form a pocket 24. These locking tubes 5 are inserted within the openings 21 in the plates 15 and are expanded to engage the same firmly by means for sliding locks 25. These sliding locks are formed of a strip of metal having one edge adapted to engage the pocket 24 and having its other edge bent to form a pocket 26 adapted to engage the free edge 27 of the tube 20. An extension 28 is provided upon the sliding locks, said extension being provided with an opening 29 to form a grip for withdrawing the sliding lock from the locking tubes 20.

In order to close the brace mold 14 I provide closure plates 30 having a flange 31 formed upon one edge and adapted to engage the rolled upper edge 32 of one of the plates 15. The other edge of the plate 30 is provided with a flange 33 adapted to embrace the outer face of the other plate 15. One end of the plate 30 is formed curved 20 for engagement with the cylindrical section 2. One side of the plate 30 is locked on the plate 15 by the aforesaid flange 31 and the other side is secured by means of a hasp 34 which is adapted to engage a staple 35 secured upon the other plate 15 and prevented from displacement by means of a locking pin 36.

When it is desired to form a post for use in corners of a fence it is desirable to use 35 two of the corner braces 14. It will be noted that these corner braces are disposed at right angles to each other, although I do not limit myself in this particular, and thus provide adequate bracing against the strain 40 of the angular fencing. When it is desired to form a post for use along straight line fences it will be found that one brace is sufficient. In order to adapt the mold for forming a post of this description, I provide 45 a plate 37 which fits within the bent strips 18 and closes the opening in the plate 8. This plate 37 is provided with a handle 38 to facilitate its removal or insertion.

In order to strengthen the lower portion 50 of the section 2, I provide a curved bar 39 which encircles the lower part of the section 22 passing through the lower locking tubes 20. The ends of the bar 39 are adapted to pass through openings 40 in angular members 41 secured upon plate 8 and are provided with openings 42 for the reception of locking pins 43.

After the mold is set up as shown in Fig. 1, the brace molds 14 may be filled with cement and the plates 30 secured in place thereon and the sections 1 and 2 filled with cement or the plates 30 may be secured in place upon the molds 14 and cement poured into the sections 1 and 2 in a sufficiently

liquid state to flow into the molds 14 through 65 the openings in the plate 8. In either event the plates 30 prevent the cement from coming out of the molds 14. The plates 5 and 7 are provided with openings 44 for the insertion of staples or other wire securing 70 means. After the mold has been removed from the molded structure, and the locking tubes 20 have been removed, the resultant holes extending through the braces are of service when fencing is secured to the post. 75 In said forms of wire stretches an anchor chain is used. These holes in the braces are particularly adapted to receive such a chain.

It will be understood that various changes in the shape, construction, and arrangement 80 of parts may be resorted to without departing from the spirit of the invention or limiting the scope of the subjoined claims.

Having thus described my invention what I claim is:—

1. A post mold comprising a cylindrical shell provided with a plurality of openings extending upwardly from its lower edge, and brace molds connected with said shell in alignment with said openings, said brace 90 molds comprising spaced parallel side plates, a detachable closure plate, and means for locking said plates in their spaced relation.

2. A post mold comprising a cylindrical shell provided with openings extending upward from its bottom edge, guides secured upon said shell adjacent said openings, and brace molds detachably connected with said shell, each of said brace molds comprising triangular side plates extending upward to 100 the top of said openings, flanges on the edges of said plates slidable within said guides, a detachable top closure plate, and collapsible means for holding said side plates in their spaced relation, either of said openings being adapted to be closed by an arcuate plate 105 slidable in said guides.

3. In a device of the character described, comprising a cylindrical shell provided with a number of openings in the lower part, a 110 brace mold comprising flanged triangular plates adapted to slidably engage guides secured upon the lower portion of said shell, a plate for closing the upper portion of said brace mold and means for locking said triangular plates in their spaced relation, said locking means comprising split tapered tubes having one edge bent inwardly to form a pocket and expanding means comprising a tapered strip having one edge 115 adapted to engage within said pocket and the other edge bent to form a pocket for engagement with the free edge of said locking tube.

4. In a mold, an upright portion having 125 openings therein extending upwardly from its lower edge, retaining strips secured to said upright portion on each side of the

openings aforesaid, triangular plates having one of their edges formed to engage said retaining strips, and also having openings therein, said triangular plates extending laterally from the upright portion of the mold, expansible tubular pieces inserted through oppositely disposed holes in said plates, a rod extending through the lowermost of said

tubes, and means to secure the ends of the rod to the upright portion of the mold. 10

In testimony whereof I hereto affix my signature in the presence of two witnesses.

SAMUEL E. SHAVER.
